G. W. METCALF AND W. H. METCALF, OF BALTIMORE, MARYLAND.

Letters Patent No. 86,240, dated January 26, 1869.

IMPROVED FIRE-BOARD.

The Schedule referred to in these Letters Patent and making part of the same.

To all whom it may concern:

Be it known that we, G. W. METCALF and W. H. METCALF, of the city and county of Baltimore, and State of Maryland, have invented a new and improved Fire-Board; and we do hereby declare that the following is a full, clear, and exact description of the construction and operation of the same, reference being had to the accompanying drawings, making a part of this specification, in which—

Figure 1 is a rear elevation;

Figure 2, a vertical cross-section through line xx of fig. 1; and

Figure 3, a front view.

The object of this invention is to construct a simple, cheap, and neat fire-board, which can readily be extended or contracted in length and width, to adjust it to fire-places of different sizes.

The board is composed of five pieces of sheet-metal, attached by suitable adjustable sliding locks, operating on its rear side, as will be hereinafter described. The central piece, which may be described as the base-plate, upon which the others are supported and adjusted, is square or rectangular. The other four pieces are each in the form of a carpenter's square, are arranged around the central piece, as shown clearly in figs. 1 and 3, being constructed to slide in and out on said piece, so as to expand or contract the size of the whole fire-board, and vary its relative dimensions as may be desired.

In the drawings—

A indicates the central piece, and

$a a a$ are four grooves on its rear side, formed by lugs soldered to it or otherwise attached, in which the blocks that hold the extension-pieces slide inward and outward.

B C D E are the extension-pieces, arranged as described, and each provided with a flange, $b c d e$, respectively, extending along the whole length of one of its outer edges, and half way from the angle to the end on the other.

Each is also provided with a flange, $b' c' d' e'$, respectively, extending the whole length of its inner edge opposite and parallel to the longer outside flange of the piece. The flanges on one end of each piece, therefore, form a socket, in which that end of the contiguous piece which is not flanged is inserted, and slides back and forth. The flanges are closely bent down, so as to hold the sliding pieces securely.

As thus constructed, the board can be expanded or contracted to any degree that may be required, not exceeding, in all, the width of the pieces B C D E.

F is a bent metallic spring-clasp, one end of which fits into the grooves $a a a$, sliding in and out in said grooves, the other end extending upward and then forward over the edge of the part B, C, D, or E, that may be adjacent to the clasp, and springing downward against or toward such edge with considerable force, in order to lock the edge of the extension-piece firmly to the centre-piece.

To assist it in doing this, an eccentric-lever, G, is pivoted to the end of it, and so arranged that when the handle of the lever is erect, or turned over backward, the pressure of the clasp on the edge of the extension-plate is but slight, if any, and the plate can be easily moved and adjusted, but when the lever is turned down, as seen in figs. 1 and 2, it presses strongly down on the edge of the extension-plate, and clasps it immovably to the centre-plate, firmly uniting the parts of the fire-board together.

The front side of the fire-board may be handsomely ornamented with a variety of designs. The whole of the centre-piece will always be shown, and may be covered with any kind of picture or design. The extension-plates will not always be fully shown, and the designs upon them should be of such a nature that as the fire-board is expanded or contracted, the design shall not be marred or its parts dislocated.

Having thus described our invention,

What we claim as new, and desire to secure by Letters Patent, is—

1. A fire-board, constructed and operating as described, so that it can be expanded or contracted to fit into fire-places of different sizes.

2. The combination of the plates A B C D E, when constructed to operate as above described.

3. The combination of the spring-clasp F with the eccentric-headed lever G, when constructed to operate in connection with the several extension-plates and the centre-plate, substantially as described.

4. The grooves $a a a$, in combination with the lock F G, so as to allow the latter to slide back and forth, substantially as described.
